UNITED STATES PATENT OFFICE.

ROBERT E. NEWCOMB, OF HOLYOKE, MASSACHUSETTS.

ELECTRICALLY-OPERATED DEVICE TO PRODUCE FLUID MOTION.

1,287,078.

Specification of Letters Patent. Patented Dec. 10, 1918.

Application filed April 28, 1913. Serial No. 764,125.

To all whom it may concern:

Be it known that I, ROBERT E. NEWCOMB, a citizen of the United States of America, residing at Holyoke, in the county of Hampden and State of Massachusetts, have invented new and useful Improvements in Electrically-Operated Devices to Produce Fluid Motion, of which the following is a specification.

10 This invention relates to electrically-operated devices for producing fluid motion. It is particularly designed for use in connection with pumping devices for elevating water or other fluids, and an object of the invention is in providing means which can be used in connection with deep or Artesian wells, since the electro-magnetic engine which is employed and which serves to reciprocate the armature may be directly connected to the piston of a pump which is located within the working barrel of the well. Heretofore, in very deep wells the rod that is connected to the piston, and generally known as the "sucker" rod, very often breaks on account of its great length and the strains imposed thereon in operating the piston. The present invention is designed to replace this rod and to locate the electro-magnetic engine or piston-actuating device directly within the well-casing or the well-barrel itself and locate it so that the armature of this engine is directly connected to the piston of the pump. A further object is to provide means for causing the electric current that flows through the coils of this engine to produce an unbalanced magnetic field directly or immediately in advance of the movement of the armature, whereby a continuous or constant pull is exerted on the 40 plunger of the pump; also to provide means for changing the direction of the electric current flowing through the coils of the electro-magnetic engine, whereby the direction of the plunger will be changed. These devices for changing the direction of the current are preferably located within the casing itself, or, if desired, they may be located above the upper end of the well-casing. In this instance a rotating commutator or slip-ring device is employed to close the circuit through the different coils of the engine for producing a constant or steady pull on the plunger. Further objects of the invention will be clearly set forth in the specification and particularly pointed out in the claims. A further object is to provide an electric re-

ciprocating engine or motor and pump combined in the same casing; to provide means to conduct the electric current to the electric engine when the latter is submerged, as in 60 wells, sumps, mines; to provide means independent of the electric engine for distributing the current to the coils of the engine; and to provide means carried within the casing and operated by the reciprocating 65 element of the engine to properly distribute the current to the coils of the motor, whereby an unbalanced magnetic pull will be exerted on the core, armature, or moving element of the engine. 70

Referring to the drawings,

Figure 1 is a vertical sectional view through the lower end of the wall-casing, the working-barrel, the electro-magnetic engine, and showing its direct connection with 75 the piston of the pump; also showing the lead-wires from the source of electrical energy that are connected to the coils of the electro-magnetic engine.

Fig. 2 illustrates the engine removed from 80 the well-casing and showing the coils within a supporting casing which retains the coils in place,—the supporting casing being an open frame-work.

Fig. 3 is a top, plan view of the construction shown in Fig. 2. 85

Fig. 4 is a vertical sectional view on the line 4—4 of Fig. 3, illustrating the armature or moving element of the engine and the coils thereof in section, also showing the 90 manner of connecting the lead-wires to the motor-coils.

Fig. 5 is a diagram showing the wiring and the manner in which the circuit is made and broken to the various coils of the engine 95 in succession as the moving element or armature travels from one end of its stroke to the other and also illustrating the key or switch-device that is operated at the end of the travel of the armature for opening the 100 circuit to some of the coils and closing it to other coils to cause the armature to reverse its direction of travel.

Fig. 6 is a modification of the means for closing the circuit to the various coils, in 105 which a rotating commutator or slip-device is used.

Fig. 7 is an end view of Fig. 6, showing the manner in which the commutator is mounted for rotation; and 110

Fig. 8 is a further modification, illustrating the switch-closing means that is as-

sociated with the moving armature or element. In this modification brushes are used to open and close the circuit to the various coils, while in Fig. 5 a small cylinder or ball 5 is employed to open and close the circuit.

Referring to the drawings in detail,—
 a designates the well-casing that is sunk into the ground after the hole has been drilled.
 b is the well working barrel and this is located directly within the well-casing and within which the valve-casing c is located at its lower end, which is preferably formed with a slight taper, indicated at d, to effect a tight joint between the casing a and barrel
 10 b. e designates the usual piston or plunger construction of the pump that is located within the casing b for drawing or lifting the water from the well and elevating it above the upper end of the casing. This plunger is formed with a threaded projection f that is secured to the connecting piece g. This connecting-piece is provided with bearings or packing rings h which work in an opening in the filling-piece i. The filling-
 15 piece is formed with an opening j in which is located a piston or bearing-member k. A plate j' closes the upper side of this opening j. The armature or moving member of the electro-magnetic engine is designated at m and the separated or spaced coils of the engine by the letter o. It will, therefore, be seen that the movable armature m of the engine is directly connected to the plunger e of the pump. The length of the opening j
 20 illustrates the extent of movement of the lifting piston o and also of the armature m. In the position shown, it is at the upper end of its stroke. In order to permit free movements of the piston k and the armature m,
 25 40 a groove or channel p is formed in the core or armature element m and extends its entire length. This groove connects the opening j with the opening q, whereby the confined air in these openings can freely circulate through the groove p from one opening to the other during the reciprocation of the armature.
 30 The coils r of the electro-magnetic engine are spaced as shown in section in Figs. 1 and 4 at o, and in side elevation in Fig. 2 in order to readily cool the same by the upward flow of the fluid. These coils are mounted in and secured to an open work-casing s, shown in Fig. 3 in the form of a cross permitting the fluid to pass upward between the coils and the outer casing a (Fig. 1), which also serves as a pole-piece.
 35 u designates the cap-member to which the casing s is attached and to which the supporting and conduit pipe v is attached. This pipe serves as a means for lifting the engine and plunger e entirely out of the well-barrel when required, and also as a water-tight receptacle to receive the electric
 40 45 50 55 60 65 wires w for furnishing current to the coils r

of the engine. The filling-piece i, which is used only with a single-acting plunger, is located between the plunger e and the engine, the connection g having a sliding movement in said piece i, and the latter, as shown 70 in Fig. 3, is provided with water-passages x parallel with its axis, as shown by dotted lines in Fig. 1. The filling-piece is not, of course, required when a double-acting plunger is used. By using a filling-piece, as i, 75 and mounting the connecting-piece g therein, it will be seen that such a construction will act as a differential plunger in a single-acting pump for the purpose of balancing the load in both directions. The action of 80 the connecting piece g as a differential plunger is more completely described as follows:—Plunger e in descending displaces the fluid between it and the foot valve c; this displacement being equal to the displacement above the plunger e less the volume of that part of the connecting piece projecting through the lower opening of the filling piece i. Therefore, inasmuch as the plunger e on the down stroke displaces on the 85 under side more than is made room for by its upper side, an amount equal to the difference (which equals the amount which g projects through the lower opening of the filling piece i) is forced up the casing. This 90 specific construction for balancing the load is, however, only illustrative, as other well-known means may be substituted where the conditions are different. One familiar with the art could, of course, make the necessary 95 change.

Referring now to the means for causing the armature m to have a reciprocating motion, reference is made to Fig. 5, in which the coils of the engine are shown at y and the armature is indicated by the reference letter p. 105 3 designates a reciprocating member or key which is attached to and moves with the plunger k. This key-member is formed with two sharply-inclined surfaces 4 and 5. The 110 terminals of the coils y of the electro-magnetic engine are indicated at 6 and 7 and are preferably composed of spring metal and which are normally in contact with each other but may be opened when one of the 115 balls, indicated at 8, is forced against the member 6 of the contacts. The lead-wires for supplying current to the coils y are designated at 9 and the various coils are connected together by the wires 10. The other 120 terminal of the coils is shown at 11. It will be seen that should current enter by the wire 9 and if all of the spring switches 6 and 7 of the coils y are closed, the current will flow directly from the wire 9 to and through 125 switches 6 and 7, connecting wires 10, and leave by the wire 11, but should the switches of the coils be opened by the key-member 3 then the current will flow through the coils and act to move the armature p by causing 130

an unbalanced magnetic field to be produced about the armature. In the position shown in Fig. 5, the switches of the coils y' , y^2 , y^3 and y^4 are open. Therefore, these 5 coils are energized by the current, the key 3 forcing the balls 8 directly against the members 6 of the switches to open the same. In Fig. 5 the armature is considered as moving upward in the direction of the arrow p' , 10 and after the armature p reaches the end of its travel it strikes the pivoted member 12, the end 12' of which engages the key 3 and forces the same downward, causing the inclined shoulder portion 5 to engage the ball 15 next in order and open the switch of the coil adjacent this ball. This operation de-energizes the coils y at the upper end of the engine, and energizes the coils at the lower end, causing the armature to be attracted in 20 the opposite direction, and it will be attracted by a constant pull in this direction by reason of the inclined shoulder 5 engaging the balls in succession and producing a magnetic field immediately ahead of the armature p . It will continue to move in this direction until it strikes the pivoted member 13, which will act in the manner described in connection with the pivoted member 12, and this operation will move the key 3 in the 25 opposite direction, cutting out the coils at the lower end of the engine and causing the coils at the upper end to be energized, whereby the plunger will be moved in a reverse direction. The key 3 is slidably mounted 30 on the plunger p in any suitable way, but it is held thereto with sufficient friction to permit it to move with the plunger and at the same time permit the pivoted members 12 and 13 to move it when the plunger reaches 35 the end of its travel.

In Fig. 6 is shown a modification for closing the circuits to the various coils of the electro-magnetic engine, the armature of which is shown at 14, and the revolving slip 40 rings or segments are indicated at 15, with which the brushes 16 engage to close the circuits to the coils 17 of the engine in the proper sequence in order to energize the coils next in order for causing the reciprocation of the armature or plunger 14. The revolving slip rings are suitably driven from some suitable independent source of power. The mounting for these rings is shown in end elevation in Fig. 7. It is to be understood 45 in connection with the revolving slip-rings that they will, of course, be located above the upper end of the well-casing and not within, as is the case in the construction shown in Fig. 5. The slip-rings 15 are 50 preferably mounted on a shaft 18 that is mounted in a suitable frame 19.

The construction shown in Fig. 8 is similar to that shown in Fig. 5, except brushes 55 are employed that are used to open and close the circuits to the coils 21 of the en-

gine. These brushes bear against a key 22 of which the parts 23 and 24 are insulated from each other, as indicated at 25. The brushes that engage the insulated portion 25 of the key 22 cause the current to flow 70 through the coils 21 to which they are connected, as shown at the points 26 and 27. As the armature 28 reciprocates, the pivoted members 12 and 13 act in the same way as that already described in connection 75 with Fig. 5 to move the key members 25. In the position shown the armature 28 has just reached the end of its up-stroke and about to commence its return downward movement. 80

It will be clearly seen by reference to Figs. 1, 2, and 4 that by reason of the spaced arrangement of the coils of the electro-magnetic engine in the open casings, they will always be maintained in a cool condition, as the fluid which is elevated by the pump circulates about and in contact therewith. This is an important feature, since the coils are confined in a close chamber below ground, and some means must be employed to keep the coils cool. The present arrangement serves very well to accomplish the desired result. 85

It is to be understood that when the term "armature" is used it applies, in general, to the moving element of the engine, and it may be convenient in some cases to maintain the core or plunger element stationary and reciprocate the field coils, and vice versa. It should also be noted that the 90 supporting pipe w serves to make watertight connections for the lead wires. The wires may, of course, be covered with fluid-proof covering and fluid-tight joints used to make the connections. 95

It is also understood that the invention is not to be limited in its application to produce fluid motion by means of a plunger, as diaphragms or pistons may be substituted wherever desired. 100

It is to be understood that I do not limit myself to the precise construction shown and described herein, as necessary changes may be made which render the structure better adapted to carry out the principles of the 115 invention; as, for example, the length of the opening j may be changed, as that shown is only illustrative of the length of the travel of the moving element of the engine; also the use of the groove p is only one 120 means of permitting the moving element to have free movements. It may, of course, be omitted altogether and the member m be made small enough for free movement during its travel. 125

What I claim, is,—

1. The combination with the casing of a fluid-motion device, and its piston located therein, of an electro-magnetic engine for operating said piston and located within the 130

casing, means to connect the piston and the moving element of the engine together, a filling-block between the piston and element, said filling block having a passageway there-
5 in for the fluid to flow through and into contact with the coils, the coils of the engine being spaced from each other for cooling purposes and arranged within the casing, the moving element of the engine being ar-
10 ranged in an air-tight casing, and means to permit the confined air therein to circulate freely from one end of the casing to the other as the moving element reciprocates.

2. The combination with the piston of a pump, of an electro-magnetic engine to operate the piston, the armature being directly connected to the piston and in axial alinement therewith, a casing to contain the engine, a filling-piece having an opening there-
15 in, a piston on the armature and located in the opening, the armature having a groove therein to permit the confined air to move freely from one end of the armature to the other, and means to energize the engine to
20 cause the armature to move in an unbalanced magnetic field, the whole being constructed and arranged within the well-casing, as described.

3. In a device to produce fluid motion, the combination, a casing, a reciprocating electric motor located therein, a plunger or suction member connected to the motor to lift or cause the fluid to move through the casing, the arrangement and construction of
30 the coils being such as to cause the pumped fluid to circulate among the coils of the motor for cooling purposes, as described.

4. In a submerged pumping mechanism, the combination with an inclosing casing, a motor and a pumping device therein, and means to operatively connect the same together, a filling-piece in which the connecting means serving as a differential piston in said cas-
40 ing, a source of energy, and means to connect the same to the motor.

5. In a device for imparting motion to a fluid, the combination with an inclosing casing-member, a motor, a pumping device
50 operatively connected to the motor and in the same axial alinement, a filling or spacing member between the motor and the pumping device and formed with passageways therethrough to permit the fluid to move
55 through the casing, said connecting means being located in the spacing member and guided thereby during its movements, a source of energy, and means to connect the same to the motor.

6. In a pumping device, the combination, an electro-magnetic engine, of the recipro-
60 cating type, a pumping device operatively connected to the engine, the coils of the motor having a space therebetween and sup-
65 ported in an open work casing, whereby

when the engine is confined in an inclosing casing, the fluid set in motion by the pumping device may circulate about said coils to maintain them in a cool condition, and means to supply energy to the engine, as described. 70

7. In a pumping device, the combination with an electro-magnetic engine including an open-work casing and coils supported thereby, of a pumping device operatively connected with said engine, an inclosing cas-
75 ing for said engine and pumping device ar-
ranged to cause the fluid pumped by the operation of the pumping device to pass around the separate coils of the engine to maintain said coils in a cool condition. 80

8. In a device for producing fluid motion, a casing serving as a fluid passage, an elec-
85 tric motor within said casing and having coils spaced from each other longitudinally and from said casing, and a pumping ele-
ment in operative relation with said motor for moving a column of fluid in the casing and freely among the spacing of the coils of the said motor.

9. In a device for producing fluid motion, a deep well casing serving as a fluid passage, an electric motor within said casing and having spaced coils, a pumping element in operative relation with said motor for mov-
90 ing a column of fluid in the casing and freely among said coils, and a conduit pipe cut off from communication with the fluid passage and accommodating means for delivering energy to said motor and affixed to the said motor to provide a means whereby the latter 100
may be withdrawn from said casing.

10. In a device for producing fluid motion, a casing serving as a fluid passage, a motor housed thereby, a pumping element in operative relation with said motor for mov-
105 ing a column of fluid in the casing, and a conduit pipe cut off from communication with the fluid passage and accommodating means for delivering energy to said motor and affixed thereto to provide a means whereby the latter 110
may be withdrawn from said casing.

11. In a device for producing fluid motion, a deep well casing having a suction and a discharge end, a motor within said suction end and remote from the discharge end and having at least a single reciprocating pump-
115 ing element in operative relation therewith and for moving a column of water through said casing, an open cage supporting said motor and permitting free circulation of fluid around the assemblage thereof, and means for delivering energy thereto and for withdrawing said motor from said casing.

12. In a device for producing fluid mo-
125 tion, a deep well casing having a suction end and a discharge end, a motor, a pumping element in operative relation therewith, means for sustaining a column of water, all located in the suction end of said casing and 130

- remote from the discharge end thereof, and means for delivering energy to said motor and for withdrawing said motor from said casing.
- 5 13. In a device for producing fluid motion, a deep well casing having a suction and discharge end, mechanism located in the lowermost end of the casing for moving a column of water through said casing in one
- 10 direction only, and comprising a motor and a pumping element in operative relation therewith, and means for delivering energy to said motor and for withdrawing said motor from said casing.
14. In a device for producing fluid motion, a deep well casing having suction and discharge ends, pumping mechanism including a motor mounted within said casing at the lowermost end for moving a column of water through said casing, and having a remote control, and means for delivering energy to said motor and for withdrawing said motor from said casing. 15 20
